FIG. 1.

FIG. 2.

INVENTOR:

F. H. Moore
by Right Brain Sunday May

ATTYS

UNITED STATES PATENT OFFICE.

FREDERICK H. MOORE, OF MELROSE, MASSACHUSETTS.

PAPER-PACKAGE.

1,252,138.

Specification of Letters Patent. Patented Jan. 1, 1918.

Application filed April 5, 1917. Serial No. 159,908.

To all whom it may concern:

Be it known that I, FREDERICK H. MOORE, a citizen of the United States, residing at Melrose, in the county of Middlesex and 5 State of Massachusetts, have invented new and useful Improvements in Paper-Pack-ages, of which the following is a specifica-tion.

This invention relates to a package com-10 posed of superimposed independent sheets of toilet or other paper, adapted to be mounted on a supporting member on which the pack-age is impaled, said member extending through the package from side to side, and 15 the sheets being adapted to be detached suc-cessively from said member by an endwise pull, causing one end of the sheet to be torn through by the supporting member.

The invention has for its object to pro-20 vide a package adapted to coöperate with a supporting member formed to support the package and prevent it from swaying or swinging edgewise, and constituting a wedge adapted to split one end of each sheet when 25 the sheet is pulled lengthwise to detach it from the member.

The invention consists in the improvement hereinafter described and claimed.

Of the accompanying drawings forming 30 a part of this specification,—

Figure 1 is a perspective view of a pack-age embodying the invention.

Fig. 2 is a perspective view of the pack-age-supporting member.

35 The same reference characters indicate the same parts in all of the figures.

In the drawings, 12 represents a portion of the back of a casing adapted to contain a package of toilet paper, and 13 represents 40 a package-supporting member which is a sheet-metal arm attached to the back 12, and made V-shaped in cross section so that it has a salient side and a reëntrant side, the

salient side facing upwardly as indicated by Fig. 2, and acting as a wedge to split 45 the upper end portions of the sheets of the pack 15, as hereinafter described.

In one end portion of the pack I form a V-shaped slot 17, Fig. 1, extending through the pack from front to rear, the salient side 50 of the slot being relatively near one end of the pack so that one end portion of each sheet is adapted to be split by the arm 13.

The pack is adapted to be impaled upon the arm 13 and to depend therefrom, the 55 main portion of the pack extending downwardly from said arm, and the rear side of the pack being supported by the back 12.

The described form of the slot 17 enables it to have a wide bearing on the supporting 60 member 13, so that the package when en-gaged with said member is prevented from swaying or swinging edgewise. Each sheet of the package is enabled, by the described form of the slot, to be easily detached, the 65 apex of the slot being nearer the upper end of the package than the ends of the slot, so that a light pull on the lower end of the sheet causes it to be torn through, or split by the member 13, between the slot apex 70 and the upper end of the sheet, with relative ease.

I claim:

As an article of manufacture, a package of superimposed paper sheets provided near 75 one end with a V-shaped slot extending through the pack from front to back, and adapted to receive a V-shaped supporting arm, the angle formed by the salient side of said slot being relatively near one end 80 of the pack, so that one end portion of each sheet is adapted to be split by said arm.

In testimony whereof I have affixed my signature.

FREDERICK H. MOORE.
